UNITED STATES PATENT OFFICE.

JAMES W. INGELS, OF CLEVELAND, OHIO.

ROOFING.

Application filed May 14, 1924. Serial No. 713,355.

This invention relates to an improvement in roofing. More particularly it includes shingles preferably formed of sheet material such as asphalt composition and the like cut 5 so as to provide a body portion and a tongue whereby the shingle is adapted to co-operate with similar shingles to form a roofing of improved appearance and having structural characteristics which prevent the elements 10 being blown up or moved out of position and affording a large degree of protection for the building to which the roof is applied at a minimum of expense for material when the features of appearance and durability are taken into consideration.

In the present invention the shingle units are preferably provided with means at their side edges for interlocking engagement with adjacent shingles and the tongues of the 20 individual shingle units are adapted to be positioned over the abutting edges of the underlying shingles so that the effect of a double-butt is obtained and the roof has the appearance of one of very substantial construction. To the accomplishment of the 25 foregoing and related ends, said invention, then, consists of the means hereinafter fully described and particularly pointed out in the claim.

The annexed drawing and the following 30 description set forth in detail certain structure embodying the invention, such disclosed means constituting, however, but one of various structural forms in which the principle of the invention may be used.

In said annexed drawing:—

Fig. 1 is a top plan view showing three superimposed rows of shingles as laid to 40 form a roof; Fig. 2 is a transverse section taken along the line 2—2 shown in Fig. 1; Fig. 3 is a plan view of a single shingle unit of full size; Fig. 4 is an end view of a shingle shown in Fig. 3; Figs. 5 and 6 are 45 plan views of one-half size shingles for use adjacent the side edges of a roof; and Fig. 7 is an end view of the one-half size shingle shown in Fig. 6.

As best shown in Figs. 3 and 4, each shingle unit 1 comprises a body portion 2 and 50 a tongue portion 3. The tongue portion of the shingle is of approximately one-half the length and width of the body portion thereof and extends downwardly centrally of the lower edge thereof. It has been found 55 that satisfactory dimensions for the body portion of the shingle are twenty inches in

length and six inches in width. The tongue portion for such shingle would be ten inches in length and three inches in width.

The shingles may be formed of any suitable sheet material such as asphalt composition and the like. In order to secure the shingles against movement the side edges thereof are provided respectively with projecting tongues and recesses which inter- 60 engage with the adjacent shingle units. As is disclosed in the drawing, the recess 4 and tongue 5 are of V-shape and positioned approximately three-quarters of the width 65 of the body portion of the shingle from its upper edge, though obviously the configuration of the tongues and recesses, as well as their number and position at the side edges 70 may be varied to suit the particular conditions of use of the roofing.

By cutting the shingle units from sheet material with the greatest length of the units disposed longitudinally thereof, there will be practically no wastage or scrap, due to the provision of the tongues and recesses, 80 inasmuch as the companion shingles will interfit when their tongues are turned toward each other.

In Figs. 5, 6 and 7, one-half size shingle units are illustrated, said units being necessary at the side edges of the roof. Said one-half size units 6, 7, may be provided with either recesses or tongues at their shorter end faces in a position to register 85 with the tongues or recesses of the full-size 90 shingle units. The tongue extensions 8 from the body portions 9 of said one-half size units are of one-half the width and length, respectively, of the body portions of 95 said units, but instead of being disposed centrally of their lower edges are adjacent one end thereof, the units for one side edge of the roof having said extensions at the left hand side of the body and those for the opposite side edge of the roof having 100 their extensions at the right hand side of the body of said one-half size units.

The manner of utilizing the shingle units is clearly shown in Figs. 1 and 2. The shingle units are laid on the roof with the 105 tongue extensions 3, 8, respectively, projecting downwardly. At the extreme lower edge of the roof these tongue extensions may be trimmed to provide a straight marginal edge. This lower row of shingles, designated A, has the tongues and recesses of 110 its adjacent units interengaged and is over-

laid by the row of shingles B. The tongue portions 3 of the shingle units B overlie the meeting edges 11 of the shingle units A, the lower edges of said tongue portions being set flush with the lower edges of the body portions of the shingle units A, thus providing the effect of a double butt at that point.

In like manner the row of shingle units C 10 is superimposed upon the row B, the tongue portions of the shingle units C overlapping the meeting edges of the shingle units B, the lower edges of said tongue portions being set flush with the lower edges of the body portions of the shingle units B, thus 15 again forming the effect of a double butt. In like manner, row upon row of shingle units is placed upon the roof until the roof is completely covered. The upper edge 20 of the roofing may be protected in any well known manner against the ingress of moisture beneath the same.

As each row of shingle units is placed upon the roof nails 12, or other fastening 25 elements, are driven through the same. The preferred position for the nails is through the body portion of the shingle adjacent the lower edge of said body portion offset outwardly from the side edges of the tongue portion. By placing the fastening 30 elements at this point the tongue portions of the succeeding row of shingle units serve to conceal the heads of said fastening elements. Also, by placing the fastening 35 elements approximately two-thirds of the distance from the upper edge of said shingle units, the same are held firmly against the roof structure and the roof is prevented from blowing up.

40 With the construction of roof, such as has just been described, it has been found that the shingle units may be applied very expeditiously and that the appearance of the roof is much enhanced over other constructions. It has also been found that by hav-

ing the tongues of said shingle units overlie the meeting edges of the preceding row of shingle units, that no open seams are exposed to the weather and it is therefore practically impossible for moisture to pass through the several layers of shingles and into the building covered by said roof.

Other modes of applying the principle of my invention may be employed instead of the one explained, change being made as regards the structure herein disclosed, provided the means states by the following claim or the equivalent of such stated means be employed.

I therefore particularly point out and distinctly claim as my invention:—

A roof formed of rows of shingles, the shingles each comprising a rectangular body portion having tongues of one-half the width and one-half the length of said body portion projecting centrally from the lower edge thereof, the shingles of one row breaking joints centrally with those of the adjacent rows, and secured by fastening elements positioned adjacent the lower edge of the body portion and outwardly from the side edges of the tongue portion, and extending through a single layer of underlying shingles, the tongues of each succeeding row of shingles being adapted to overlap the meeting lines at the ends of the respective shingles of the preceding row, thus enclosing the lower portion of said joined shingles between two unbroken shingle layers and providing three layers of material over the area of each tongue portion, the lower edge of each tongue portion being set flush with the lower edges of said body portions of the two adjacent shingles of the preceding row, said tongue being of equal transverse extent thereto and providing the effect of a double butt.

Signed by me, this 10th day of May, 1924.

JAMES W. INGELS.
